UNITED STATES PATENT OFFICE

2,008,104

ELECTRIC METER COVER

Orla E. Juvinall, Danville, Ill., assignor of one-half to George E. Martin, Danville, Ill.

Application June 12, 1934, Serial No. 738,302

4 Claims. (Cl. 229—4)

This invention relates to an electric meter cover.

An object of the invention is the construction of a simple and efficient cover for the entire electric meter, so as to prevent same from being tampered with, or the current fraudulently utilized, whether the electric current is in operation or not; further, by running the service wires into the cover, they cannot be tampered with or the current used even if the meter is entirely removed from the cover.

Another object of the invention is the construction of a simple and efficient cover device for the entire meter, including the wires, which device can be manufactured at a relatively low cost.

Another object of the invention is to improve the construction of the device disclosed in my former patent No. 1,946,796, issued February 13, 1934.

With the foregoing and other objects in view, my invention comprises certain novel constructions, combinations and arrangements of parts as will be hereinafter fully described, illustrated in the accompanying drawings, and more particularly pointed out in the appended claims.

In the drawings:

Figure 1 is a perspective view of a device constructed in accordance with the present invention, while

Figure 2 is a view in front elevation of the same.

Figure 3 is a top plan view of the device, while Figure 4 is a bottom plan view of the same.

Figure 5 is a vertical, central, sectional view of the device.

Figure 6 is a view in elevation of the back section looking at the inside thereof.

Figure 7 is a view in elevation of the front section, looking at the inside thereof.

Figure 8 is a sectional view taken on line 8—8, Figure 6 and looking in the direction of the arrows.

Figure 9 is a fragmentary, perspective view of the device showing the novel locking means for holding the sections in a locked position.

Referring to the drawings by numerals, 1 designates a casing upon which comprises the front section and the back section 3. The back section 3 is provided with a wire receiving portion 4 (Fig. 6) and the meter-body receiving portion 5. The back section is formed of suitable material as well as the front section 2. The outer edge of the back section is bent over, as at 6 (Figs. 8 and 9) and terminates in a right angled or a horizontal flange 7. In the meter-body receiving

portion 5 I have fastened vertically two Z-shape pieces 8, 8 that produce a slot for the nut 9 and screw 10; nut 9 and screw 10 may be slid vertically in the slot formed by said Z-shape pieces 8 to permit adjustment of the meter dial so that it may be read accurately through the glass 11 held against the inner face of the meter-body receiving portion of the front section 2. This glass 11 is held in place by angle brackets 12.

The front section 2 is adapted to fit upon the back section 3, with its reinforced edge 13 (Fig. 5) limited in its inward sliding movement by resting against the outwardly extending flanges 7 of the back section. This reinforced edge 13 of the front section is formed by bending or casting the edge-material back upon itself as is shown in Fig. 5.

The front section is provided in its top with a depending spur lug 14. This spur lug fits into aperture 15 formed in the top of the back section 20 to hold the top portions of both sections together, but readily permitting the front section to be removed when the locking means at the bottom of the sections is detached, as will be hereinafter described.

Various size knock-outs 16, as indicated by the dotted circles, may be formed upon the back section for receiving pipe and suitable fittings. As indicated at 17 a female thread fitting may be also used as a part of the device instead of using 30 knock-outs 16, if preferred. Further, as indicated at 18 a male thread fitting may be used as part of the device in preference to the knock-out 16.

The back section is provided in its rear and near the top, with preferably two apertures 19 for fastening the device in place, wherever used, because suitable nails, screws or the like can be inserted through these apertures into the supporting wall or surface of the building in which the device is placed.

A lid 20 is pivoted at 21 upon the outer face of the front cover 2 to protect the glass 11 against breakage, etc. However, the lid can be easily pivoted to one side so that the dials 22, Fig. 2 may be easily read or viewed.

The locking means for fastening the bottom of the front and rear sections together comprises two apertured lugs 23 fastened to the bottom of the back section 3. These lugs 23 are spaced to receive therebetween two engaging lugs 24 formed 50 on the bottom of the front section 2. The lugs 24 extend rearwardly and horizontally from the reinforced edge 13 of the front section, as will be clearly seen in Fig. 5. These lugs are apertured, as well as lugs 23 to receive the bolt 25. Bolt 25 55

is provided on its outer end with aperture 26, through which the seal wire 27 extends. A butterfly nut 28 is on bolt 24; this nut is provided with two apertures 29 through which seal wire 27 passes, Fig 4, and on wire 27 is a suitable seal 30, whereby the device is securely locked against fraudulent tampering. When the sealing means including bolt 24 is removed from the registering lugs of the two casings, then the front casing can be swung outwardly at its bottom, and then lifted up to disengage lug 14 from aperture 15, whereupon the front section can be entirely removed.

From the foregoing it will be understood that I have produced a novel and efficient device for enclosing the entire meter and its wires. This device can be easily applied or removed. The operator can officially inspect the electric meter, either to read the dials, or when it is necessary to examine the interior of the meter, for the assembling and disassembling of the front section from the rear section is simply accomplished.

While I have described the preferred embodiment of my invention and illustrated the same in the accompanying drawings, certain minor changes or alterations may appear to one skilled in the art to which this invention relates, during the extensive manufacture of the same, and I, therefore, reserve the right to make such changes or alterations as shall fairly fall within the scope of the appended claims.

What I claim is:

1. In a device of the class described, the combination of a back section provided with depending spaced apertured lugs, a front section on said back section and provided with depending abutting apertured lugs extending between said spaced lugs on said back section, and fastening means in

said registering lugs for locking the sections together.

2. In a device of the class described, the combination of a back section provided with depending spaced apertured lugs, a front section on said back section and having a reinforced edge, parallel-engaging and rearwardly-extending lugs integral with the reinforced edge of the front section and positioned between said spaced apertured lugs, a bolt in all of said lugs, a nut provided with apertures, said bolt provided with an aperture contiguous to the apertures of said nut, and a seal wire provided with a seal threaded through all of said apertures, substantially as shown and described. 15

3. In a device of the class described, the combination of two sections, one slideable upon the other, said sections provided at their engaging portions with parts of the body bent back upon themselves to form reinforcing edges, one of said reinforcing edges provided with a right-angled integral flange, said flange engaged by the reinforced portion of the other section to limit its sliding movement in one direction, and means for locking the sections together. 20

4. In a device of the class described, the combination of a back section provided in its top with only a central aperture, a front section on said back section and provided in its top with only a depending central spur lug fitted in said aperture 30 whereby said front section may swing freely outwardly at its bottom, and manually operated locking means on the lower portion only of said back and front sections for normally holding said front section from outward swinging. 35

ORLA E. JUVINALL.
